AUTOMATIC LIQUID-SEPARATOR.

No. 896,262.

Specification of Letters Patent.

Patented Aug. 18, 1908.

Application filed June 24, 1907. Serial No. 380,589.

To all whom it may concern:

Be it known that I, OSCAR ZERKOWITZ, a citizen of Austria-Hungary, residing at Cleveland, in the county of Cuyahoga and State of Ohio, have invented certain new and useful Improvements in Automatic Liquid-Separators, of which the following is a specification.

My invention relates to improvements in automatic liquid-separators, being primarily designed for the separation of liquids of different specific gravities.

The invention relates more particularly to separators for separating water from gasolene, being specially designed for use in connection with the gasolene tank of automobiles, motor-boats etc., and the primary object of the invention is to separate the major portion of the water through the medium of the force of gravity in connection with a float-controlled valve, and the minor portion of the water by combining with said means communicating-chambers provided at their upper portions with outlet-openings covered with foraminous material so that the lighter liquid is first brought into contact with the foraminous material from below thus preventing the weight of the lighter liquid from acting to press or carry with it the heavier liquid, as is the case when the liquids are brought into contact with the foraminous material from above, by the force of gravity, as is the case in an ordinary funnel-shaped strainer, or the like.

With these and other ends in view, the invention consists in the novel construction, arrangement and combination of parts, hereinafter described, illustrated in the accompanying drawings, and particularly pointed out in the appended claims.

Referring to the drawings, forming a part of this specification, Figure 1, is a vertical central sectional view of the improved separator. Fig. 2, a cross sectional view taken through line II-II, of Fig. 1. Fig. 3, a top plan view of the same.

Similar characters of reference designate like parts throughout all the figures of the drawings.

The preferred form of the improved separator comprises a cylindrical main body portion 1, and is designed to be mounted in a vertical position within the gasolene-tank or receptacle (not shown) and is secured to the upper and lower walls 2, thereof, by means of upper and lower flanged rings 3, and 4, re-

spectively, said rings being secured to the cylindrical body 1, and having their flanged portions secured to said upper and lower walls 2, of the receptacle, by means of rivets 60 and soldering.

A second or inner cylindrical body portion or vessel 5, is mounted concentrically with the first or outer body portion 1, by means of an upper ring-head 6, having exterior threads 65 to engage with interior threads of the upper flanged ring 3, and a lower depending flanged head 7, terminating in a central discharge-pipe 8, the depending portion 7^a, of said head 7, taking into and fitting within a central 70 opening of a flanged ring or head 9, secured within the lower end of the outer body portion 1. The shoulder portion 7^b, of the head 7, rests upon an annular packing-gasket 10, interposed between the same and the ring or 75 head 9, and is designed to prevent leakage at this point of the fluid contained in the annular receptacle 11, formed between the walls 1, and 5.

A float-controlled valve is mounted within 80 the depending portion of the head 7, and just above the discharge-pipe 8, by the following described means, viz.: A supporting-plate 12, secured to the head 7, by means of bolt supporting-sleeves 13, and bolts 14, said 85 bolts having rivet-heads 14^a, and extending through the ends of the plate 12, sleeves 13, and the head 7, and provided at their lower ends with lock-nuts 15. Washers or packing-gaskets 16, are interposed between the lower 90 ends of the sleeves 13, and the head 7, to prevent leakage through the bolt-holes of the latter. A pair of standards or arms 17, are mounted upon the plate 12, terminating at their upper ends in lugs 17^a, in which are secured lever-arms 18, by means of pivot-pins 19, the outer or movable ends of the lever-arms 18, being provided with slotted openings 20, and, near their fixed pivot-ends with slotted fulcrum-openings 21, carrying a cross-pin 22, taking through the upper end of a vertically-arranged movable valve-stem or bolt 23, slidably-mounted in a guide-sleeve 24, of the plate 12. Disk-valve-plates 25, and 25^a, are secured to the lower end of a 100 valve-stem or bolt 23, by means of a locked-nut 26, and a disk of suitable resilient material 27, preferably of cork, is interposed between the plates 25, and 25^a, the lower plate 25^a, being of such diameter as to expose an annular valve-bearing-surface 27^a, 105 to impinge upon a valve-ring 28, preferably

of German silver, about the upper edges of the discharge-pipe 7. The cork is used as a packing material because it is a resilient material that is least affected or deteriorated by 5 the action of the gasolene.

The float consists of an air-tight cylindrical vessel 29, concentrically-arranged within the walls of the inner vessel 5, by means of cross-arms 30, extending through the vessel 29, 10 and the ends thereof impinging against the inner surface of the vessel 5. The lower end of the vessel 29, is provided with a flanged head 31, carrying a disk-weight-block 32, preferably of lead, mounted above and within 15 the vessel 29, by means of a central bolt 33, and disk-cap 34. The flanged head 31, is provided near its edges with depending lugs 35, within which are secured the outer movable ends of the lever-arms 18, by means 20 of cross-pins 36. It will be observed that the force exerted by the upward and downward motions of the float is greatly multiplied at the valve.

The tank is filled through the separator, 25 the fluid being poured into the upper end of the separator which is provided with a cap or head 37, having a central wrench-head opening 38, and a depending rim 39, said rim being screw-threaded on its interior to engage with the exteriorly-threaded flanged ring 3, and an annular flange 40, to bear 30 against the flanged portion of said ring 3, a packing gasket 41, being interposed to prevent leakage etc.

35 A central depending portion 42, of the cap 37, is adapted to impinge upon a head 43, of the float 29, when the cap is in its closed position, thus normally keeping the float down and preventing the opening of the attached valve when the separator is closed, as 40 against the jar incident to the running of the automobile.

A series of openings 44, covered with very fine gauze, or other foraminous material is 45 formed near the upper ends of the outer and inner walls 1, and 5, through which the lighter liquid passes into the tank or receptacle.

The annular chamber 11, formed between 50 the walls 1, and 5, communicates with the main chamber 45, of the receptacle by means of a plurality of openings 46, near the bottom thereof.

The provision of the outer wall or vessel 1, 55 is for the following purposes: First: to form communicating chambers by means of openings in their upper and lower portions, said upper openings being covered with foraminous material, whereby the lighter liquid is 60 first brought into contact with the foraminous material and in such a manner as to prevent the weight of the lighter liquid from carrying with it the heavier liquid through the foraminous material covering the openings. Second: to allow the working parts of

the separator to be readily and quickly removed from the tank for repair or inspection. Third: to form a better and more convenient connection between the body portion of the separator and the upper and lower walls of 70 the tank, as well as to provide for a convenient fastening device or mounting for tanks of various depths.

The operation of the separator, taking for example its operation in separating water 75 from gasolene, is as follows: The present form of separator is adapted to separate endless quantities of liquids of different specific gravities, and is adapted to separate the liquids simultaneously and in substantially 80 two constant streams while the mixture is being poured into the top of the separator, the lighter liquid or gasolene being adapted to pass through the outlet-opening 44, covered with foraminous material, while the 85 heavier liquid, or water, is adapted to pass through the discharge-pipe 8, by the opening of the float-controlled-valve. When the mixture is poured into the separator, it immediately finds its way into and fills the 90 annular space or main chamber 45, between the walls of the float 29, and the walls of the inner vessel 5, and the agitation and circulation of the liquid therein caused by the falling stream of the pouring liquid engenders 95 many little and mixed particles of both liquids in the form of many millions of drops or air-bubbles.

It will be observed that the annular space filled by the circulating liquid is quite narrow and deep, and the liquid in the lower or base portion of the annular space and about the float-controlled valve is more quiescent or placid than in the upper portion into which the mixture is being poured, and, consequently, a stratification of the liquids is 105 permitted throughout this portion of the receptacle, the heavier liquid settling and rising about the float to a substantially predetermined height as will now be explained. 110

It is obvious that the character of the float should be such that it will float in the water or heavier liquid and will sink in the gasolene or lighter liquid.

It will be understood from the above that 115 it will be impossible for the float to rise when the liquid surrounding, or almost entirely surrounding, the float is not made up of the heavier liquid only, but of a mixture of both liquids or intermixed with air-bubbles. In 120 such case, if the mixture is raised and brought into contact with the foraminous material, in the present instance in the form of very fine wire gauze, covering the openings 44, the turbulent fluid is broken and enters 125 the annular chamber 11, as a placid stream.

The fluid filling the annular chamber 11, is quiescent and enters the main chamber 45, of the receptacle through a plurality of openings 46, near the bottom thereof, so that 130

should any of the heavier fluid pass into the chamber 11, it will settle and tranquilly pass through the openings 46, into the lower portion of the main chamber 45, thus further contributing to the quiescence of the liquid in this portion of the chamber. Furthermore, it has been found that when the mixture is brought into contact with the wire gauze as per arrangement of the parts and under the conditions shown and described, the wire gauze has the property of separating or "screening out" the heavier liquid, provided the opposite side of the gauze has not become moistened by, or wet with, the heavier liquid.

Having thus described my invention, what I claim and desire to secure by Letters Patent, is,—

1. In a separator, a tank, an inner and an outer vessel forming chambers communicating with each other by means of foraminous material in the upper portions of said vessels, and a float-controlled valve mounted in one of said chambers.

2. In a separator, a tank, inner and outer vessels forming main and annular chambers, respectively, communicating with each other and with said tank by means of openings in their upper portions covered with foraminous material, and a float-controlled valve mounted in the lower portion of said inner vessel.

3. In a separator, a tank, an inner and an outer vessel communicating with each other and with said tank by means of openings in their upper portions covered with foraminous material, and a float-controlled valve mounted in said inner vessel.

4. In a separator, a tank, a plurality of communicating vessels mounted in said tank, a float-controlled valve mounted at the lower end of said vessels, and communication formed between the upper portions of said vessels and said tank by means of foraminous material.

5. In a separator, inner and outer vessels forming main and annular chambers communicating with each other by means of a plurality of openings, in the upper portions of said vessels, covered with foraminous material and uncovered openings in said inner vessel below said covered openings.

6. In a separator, an outer vessel provided at its upper portion with a plurality of outlet-openings, an inner vessel forming an intermediate annular chamber and provided at its upper and lower portions with a plurality of openings communicating with said annular chamber, said openings in the upper portion of said inner vessel being provided with foraminous material.

7. In a separator, the combination with an inner vessel provided with a float-controlled valve; of an outer vessel forming an annular chamber intermediate said inner and outer vessel, outlet-openings covered with

foraminous material formed in the upper portions of said inner and outer vessels, and inlet-openings in the lower portion of said inner vessel.

8. In a separator, the combination with a cylindrical main body portion provided at its upper portion with a plurality of outlet-openings covered with foraminous material; of a second cylindrical body portion mounted within said main body portion and provided with a plurality of inlet-openings covered with foraminous material in its upper portion, said second or inner body portion forming, conjointly with said outer main body portion, an annular chamber communicating with said inlet and outlet openings.

9. A separator, comprising an inner and outer vessel forming main and annular chambers, respectively, communicating with each other by means of a plurality of upper and lower openings, said upper openings being covered with foraminous material, and said inner vessel being provided with a valve-opening and a float-controlled valve.

10. A separator, comprising a cylindrical body portion provided at its top with a series of discharge-openings and at its lower ends with a head having a centrally-located discharge-pipe, a valve mounted immediately above said discharge-pipe and provided with a valve-stem, a supporting-plate mounted above said valve and secured to said head, a pair of standards mounted upon said supporting-plate, a pair of oppositely-disposed lever-arms pivotally-secured at one end to said standards and provided near their fulcrums with a common cross-pin carrying said valve-stem, and a hollow cylindrical float concentrically-arranged within said cylindrical body portion and secured to the outer ends of said lever-arms.

11. A separator, comprising an outer vessel or main body portion provided with a plurality of outlet-openings covered with foraminous material, an inner vessel forming an intermediate annular chamber within said outer vessel and provided at its lower end with a plurality of inlet-openings and at its upper end with outlet-openings covered with foraminous material, and a valve-opening normally closed by means of a valve and float mounted in said inner vessel.

12. In a separator, a tank, an outer vessel mounted in said tank and communicating therewith by means of foraminous material, an inner vessel forming an annular chamber intermediate the walls of said vessels and provided with outlet and inlet-openings, said outlet-openings being covered with a foraminous material, a valve normally closing said valve opening, and a float connected to said valve and mounted in said inner vessel.

13. In a separator, the combination with a cylindrical body provided near its upper end with a plurality of outlet-openings and at its

lower end with a head having a discharge-opening, a valve mounted above said discharge-opening, and a float secured to said valve and concentrically mounted in said 5 cylindrical body; of a cap or head secured to said cylindrical body and resting against said float whereby to normally close said valve.

14. In a separator, the combination with a main body portion provided at its upper portion with a plurality of outlet-openings covered with foraminous material and at its lower end with a head having a discharge-opening, a valve normally closing said discharge-opening, and a float secured to said 10 valve; of a cap or head mounted on said main body portion and resting on said float whereby to close said valve.

15. A separator, comprising a casing provided with a plurality of openings, covered 20 with foraminous material, at its upper portion and at its lower end with a head having a discharge-opening, a valve mounted above said discharge-opening, a float secured to said valve, and a head or cap adapted to rest 25 on said float when in its closed position.

16. A separator, comprising a double-walled casing providing an intermediate annular chamber and a main chamber communicating with each other by means of a plurality of outlet and inlet-openings formed in the walls of said inner casing, said outlet 30 openings being covered with foraminous material, a valve-opening formed in the lower

end of said inner casing, a valve normally closing said valve-opening, a float connected to said valve, and a plurality of outlet-openings formed in said outer casing and covered with foraminous material. 35

17. A separator, comprising a tank, a vessel intersecting the upper and lower walls of the tank and provided with outlet-openings, covered with foraminous material, communicating with said tank, a head secured to said separator vessel and provided with a discharge-opening outside of said tank, and a 40 float-controlled valve normally closing said discharge-opening.

18. In a separator, a plurality of vessels forming communicating chambers provided with openings covered with foraminous material, a valve opening, a valve normally closing said valve-opening, and a float connected to said valve. 50

19. A separator, comprising a tank, a plurality of vessels communicating with each other and with said tank by means of foraminous material, a float-controlled valve formed in one of said vessels, and an inlet-opening leading from said vessel containing 55 said float-controlled valve.

In testimony whereof I have affixed my signature, in presence of two witnesses.

OSCAR ZERKOWITZ.
